Charles A. Shaeffer.
BY *Arthur C. Brown.*
ATTORNEY.

UNITED STATES PATENT OFFICE.

CHARLES A. SHAEFFER, OF KANSAS CITY, MISSOURI, ASSIGNOR OF ONE-THIRD TO HARRY E. SHERMAN AND ONE-THIRD TO LOUIE A. SHERMAN, BOTH OF KANSAS CITY, MISSOURI.

SHOTGUN SHELL.

Application filed May 2, 1921. Serial No. 466,021.

To all whom it may concern:

Be it known that I, CHARLES A. SHAEFFER, a citizen of the United States, residing at Kansas City, in the county of Jackson and State of Missouri, have invented certain new and useful Improvements in Shotgun Shells; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to fixed ammunition and particularly to ammunition to be used in shot guns. The invention contemplates an inexpensive construction of shell in which the paper tubular portion can be efficiently secured to the metallic cap so that liability of distortion of the shell when in use may be eliminated, it being one of the prime objects of my invention to inexpensively and efficiently secure the paper body portion of the shell to the cap. It is also the purpose of my invention to generally improve the construction of fixed ammunition for shot guns, and to this end the invention consists in certain novel parts and combinations of parts, all of which will be specifically referred to hereinafter, reference being had to the accompanying drawings, in which

Fig. 1 is a perspective view of a completed shell constructed in accordance with my invention, parts being broken away to show the interior construction thereof.

Fig. 2 is a perspective view of the paper tube and the base wad, part of the tube being broken away to show the base wad, the end of the tube being shown preparatory to being crimped over the wad.

Fig. 3 is a similar view of the base and of the tube crimped over the wad.

Fig. 4 is a like view with the metallic base disk for securing the base wad and tube together, and

Fig. 5 is a similar view of the tube, base wad and the base cap and the primer cap assembled.

In carrying out my invention, I prefer to provide a tube 1, preferably of paper and of appropriate length, into one end of

which may be inserted a base wad 2, preferably of soft and flexible material. The base wad 2 has an opening 3. After the base wad and tube 1 are assembled as shown in Fig. 2, the projecting end 4 of the tube 1 is crimped over against one end of the base wad. A base cap 5 is then sleeved over the tube 1. The cap consists of a disk base 6 and an outer flange 7. Then the cap is subjected to the action of a die which will strike a plurality of tubular engaging projections 8 and force them through the inturned end 4, as shown in Fig. 4, the die being so constructed that at the same time a circular flange 9 will be struck therefrom to lie against the inner wall of the opening 3, so that the base wad 2 and the tube 1 will be crimped between the flanges 7 and 9, and the inturned end 4 of the tube 1 will be anchored by the engaging projections 8 on the base cap 5, thus securing the parts together. A primer cap 10 is next applied. The primer cap consists of a disk 11 carrying primer 12 which is insertible into the opening 3 of the base wad 2, the primer being held by the inturned flange 13 on the disk 11. The disk 11 is also provided with an exterior or peripheral flange 14 which is adapted to lie against the outer face of the flange 7 on the base cap 5. When the parts are assembled, as shown in Fig. 5, a rim 15 may be crimped around the primer cap, and the crimping action also forms a rim 16 about the periphery of the base cap so that the two caps will be secured together, and the tube 1 will be slightly constricted so as to bind against the base wad 2, and since the base wad 2 is preferably of soft material, part of it will be forced into the space formed between the inner edge 18 of the inturned end 4 and the flange 9 of the base cap, as clearly seen in Fig. 1. Such a construction may be inexpensively provided, and it will be apparent from Figs. 1, 4, and 5 that the projections or tines 8 will be embodied in the inturned end of the tube 1 so that the tube can not become accidentally disassociated with its base wad. Therefore, a hollow shell of considerable strength may be manufactured.

The shell may be loaded in the usual way by providing the powder charge 19 in the space immediately in front of the primer

12, introducing a hard wad 20, one or more soft wads 21, and finally the shot or projectiles 22.

The end opposite to the base of the shell 5 is closed in the usual manner by a hard wad or disk and the shell tube crimped over it as is a common practice.

What I claim and desire to secure by Letters-Patent is:

10 1. A shell comprising a tube, a base wad within the tube, a flange on the tube against the base wad, a base cap having an outer flange engaging over the tube, projections 15 on the base cap engaging the flange on the tube, an inner flange on the base cap projecting into an opening in the base wad, and a primer cap having a flange overlapping the outer flange on the base cap, and provided with a primer extending into the 20 opening in the base wad.

2. A shell comprising a paper tube, a metallic base cap having a central flange surrounding and concentric with an open-

ing therein, a peripheral flange overlapping the tube, an inturned end on the tube, means 25 on the cap engaging said inturned end, a base plug bearing against one face of the inturned end and having an opening to receive the concentric flange of the cap, and a flanged primer cap over the base cap. 30

3. A shell comprising a fibrous tube having an inturned end, a base wad bearing against the inner face of the inturned end of the fibrous tube and having a central opening, a base cap bearing against the 35 outer face of the inturned end of the fibrous tube and having an upset portion embedded in the outer face of the inturned end, and a flanged primer cap over the base cap provided with a central primer receiving opening, having an inturned flange at the edge thereof extending into central opening in the base wad.

In testimony whereof I affix my signature.

CHARLES A. SHAEFFER.
